W. Arthur,

Fire Engine.

No 23,435

Patented Apr. 5, 1859.

Fig. 1.

Fig. 2.

UNITED STATES PATENT OFFICE.

WILLIAM ARTHUR, OF BROOKLYN, NEW YORK.

IMPROVED ARRANGEMENT FOR EXTINGUISHING FIRES IN STEAM VESSELS.

Specification forming part of Letters Patent No. **23,435**, dated April 5, 1859.

To all whom it may concern:

Be it known that I, WILLIAM ARTHUR, of Brooklyn, county of Kings, State of New York, have invented a new and Improved Mode of Flooding Steam-Vessels with Water for the Purpose of Extinguishing Fire; and I do hereby declare that the following is a full and exact description thereof, reference being had to the accompanying drawings, and to the letters of reference marked thereon.

The nature of my invention consists in the application of the ample power and supply of water furnished and always ready in every vessel having a condensing-engine for propulsion, for the purpose of flooding the decks or holds of the vessel in cases of fire by using the power of the engine communicated to the air-pump and the discharge-water from the air-pump for that purpose.

To enable others skilled in the art to make and use my invention, I will proceed to describe its construction and operation.

Figure 1 is a side elevation of that part of a condensing-engine used on board steam-vessels, known as the "air-pump" and "hot-well" with rising pipe; and Fig. 2 is an end elevation of the same, all shown in black ink, the same letters in both figures indicating similar parts.

A is the bed-plate with that part through which the main center of the side levers is shown.

B is the air-pump, which discharges into the hot-well shown in that part inclosed by the dotted lines in Fig. 1 at C, through which the air and water are discharged, as usual, through the side opening at D, and air ascending through the rising pipe E, and for the purpose of using this large supply of water constantly at command I attach to this rising pipe E a continuation, as shown in red lines, which may be raised to any required height, if necessary as high as the gangway of the paddle-box in side-wheel steamers, with branch pipes, as at F, to the deck, to the cabins, or to the holds, as may be desirable, and the rising pipe ending with a branch to carry off the discharge-water should it be allowed to rise that height. For the purpose of

directing the flow of water, I employ valves, and prefer that kind known as "sluice-valves," as represented at F and G, which valves can be easily operated on by handles on the deck of vessel and under the charge of a fire-warrior appointed from the ship's crew for that office. Immediately, in case of fire, the sluice-valve G is shut, stopping off the ordinary discharge, the water immediately ascends in the hot-well C up through the pipe E into the continuation (represented in red ink) to the first discharge-pipe at H, where the water may be directed as required. If these valves are shut, it will ascend to the second discharge-pipes at I, supposed to be on deck, which will direct the flow on deck on either side, as required, and if, through inadvertency, the sluice-valve G should be closed, and the other valves, as at F, not opened soon enough to take away the supply of water, the flow of water will be carried off by the discharge-pipe J over the side of vessel. There are circumstances of construction of engines that may vary the manner of attaching this pipe to the discharge-pipe; but the manner as shown in the drawing appears to be most suited to that style of engine known as "side-lever" engines, or the ascending pipe may be inserted into an air-vessel for the purpose of relieving the air-pump from the shock when the bucket strikes the water, all which are well known to persons employed in such constructions.

Having thus described the means I employ for obtaining a supply of water and the mode of operating the same, what I claim as my invention, and desire to secure by Letters Patent, is—

The application of the waste water discharged from the air-pump raised to such height as to flood the steam vessel with water for the purpose of extinguishing fire, as herein described, instead of discharging it, as usual, as waste water from the sides of the vessel.

WILLIAM ARTHUR.
